SPINNING OR TWISTING RING

Robert Y. McLeod, Bishopville, S. C., assignor to
James McD. McLeod, Bishopville, S. C.

Application April 20, 1936, Serial No. 75,433

6 Claims. (Cl. 118—59)

This invention relates to a spinning ring or twisting ring and more especially to a ring capable of having a traveler attached thereto or removed therefrom without the necessity of bending or distorting the traveler. In spinning yarn it often becomes necessary to change the traveler for spinning a different count of yarn which is being spun, as where a different yarn count is being produced it is necessary to have a different traveler. During a change it is necessary to temporarily distort the traveler a sufficient amount to allow it to be inserted over the rims of the spinning ring and as a consequence, the traveler is very often damaged or fractured. Also, in present spinning rings, the traveler must have a degree of softness to provide sufficient resiliency in the traveler to spring enough to pass onto or off the ring. With my improved ring this resiliency in the traveler is not required, hence the traveler can be made much harder and therefore will wear longer than travelers heretofore used.

It is, therefore, an object of this invention to provide a spinning ring which has means embodied for allowing the attachment or removal of a traveler without distortion of the same or interference with the operation thereof.

It is a further object of this invention to provide a spinning ring having a cutaway portion in the rim thereof to provide a passageway through which the open segment of the traveler is adapted to pass and with means for closing said opening to securely lock the traveler upon the ring.

By providing a spinning ring of this type it will allow the traveler to be constructed from material having a greater degree of hardness thereby increasing the life and durability of the same, because it is necessary for the traveler in the conventional construction to be soft enough to allow it to spring over the flanges or rims of the spinning ring when it is being affixed or removed therefrom.

Due to the fact that the traveler, associated with this mechanism, is harder and is without the usual resiliency, it cannot be pulled off of the flange of the ring by the yarn when its tension varies. The existing undesirable condition termed "travelers flying off" is eliminated.

Some of the objects of the invention having been stated other objects will appear as the description proceeds when taken in connection with the accompanying drawings, in which:—

Figure 1 is a plan view of a spinning ring constructed in accordance with my invention with a traveler mounted thereon;

Figure 2 is an elevation of Figure 1;

Figure 3 is an enlarged detailed view of a portion of Figure 1 showing the closure means in an opened position ready for the insertion or the removal of a traveler;

Figure 3A is a view similar to Figure 3 but showing the closure means in a closed position;

Figure 4 is a sectional view taken along the line 4—4 in Figure 2;

Figure 5 is a sectional view taken along the line 5—5 in Figure 3 and showing a traveler mounted on the ring;

Figure 6 is an enlarged top plan view of a portion of a spinning ring showing a slightly modified form of the invention;

Figure 7 is an elevation of the portion of the ring shown in Figure 6;

Figure 8 is an isometric exploded view of a portion of the ring and the spring-pressed dog adapted to be attached thereto;

Figure 9 is a plan view of a twisting ring with a traveler mounted thereon showing a slightly modified form of the invention;

Figure 10 is an elevation of Figure 9;

Figure 11 is a view similar to the central portion of Figure 10 but showing the pivoted closure means in an open position;

Figure 12 is a sectional view taken along line 12—12 in Figure 11;

Figure 13 is a plan view of a portion of a ring showing another slightly modified form;

Figure 14 is an elevation of the portion of the ring shown in Figure 13;

Figure 15 is an isometric exploded view of a portion of the ring with the spring pressed dog adapted to be attached thereto.

Referring more specifically to the drawings, the numeral 10 denotes a spinning ring having upper horizontally disposed flanges 11 and a suitable collar 12 integral therewith. The collar 12 is adapted to fit down against the upper portion of a ring rail when installed. A traveler 13 is adapted to be mounted on the ring 10, said traveler having its inturned ends projecting beneath the flanges of the ring 10 in order that it may be secured thereon. In this position the traveler is adapted to encircle the ring during a spinning or twisting operation.

The end 13a of the traveler normally contacts the lower surface 11a of the flange 11 under the tension of the yarn and thus end 13b of the traveler is thus held out of contact with the lower surface 11b of the flange and therefore any roughness which might occur in the joint between 50 55

the gap and the closure member will not affect the operation of the traveler.

In order to insert the traveler 13 over the flange 10 without the necessity of bending or 5 distorting the same, a suitable dog 15 is pivoted as at 16 to a flange 11. Also at this point a suitable notch or slot 17 has been cut in the outside flange 11 in which the dog 15 is adapted to fit after the traveler has been inserted upon the 10 ring for operation.

A recess 18 is cut in the upper flange adjacent the slot 17 in which the tongue portion 15a, which is integral with dog 15, is adapted to be inserted. When the portion 15a is inserted within 15 in the recess 18 the dog 15 is held in aligned position with relation to the flange 11 in such a manner that there will be no obstruction to interfere with the movement of the traveler 13. When the dog 15 is in a closed position, namely, in the position shown in Figures 1 and 2, the friction between the recess 18 and the portion 15a holds the same in a closed position. A suitable spring 20 normally contacts the end 15b of the dog 15 to hold the dog in whatever position it may occupy.

In the form shown in Figures 1 to 5 inclusive, the friction between the parts holds the dog 15 in closed position, and the pressure of spring 20 increases the friction on the end 15 and thus assists in holding the dog in closed position. Even if the dog should accidentally move to open position, the moving traveler would move it to closed position.

Figures 6, 7 and 8 show a slightly modified form 35 of the structure in which a dog 25 having a spring portion 26 integral therewith is adapted to be secured as at 27 to the upper portion of flange 11. Likewise a slot 28 is cut in the upper flange of the ring, said slot having bevelled surfaces 29 and 30 which are adapted to be normally contacted by bevel surfaces 31 and 32 respectively of dog 25. The resiliency of the spring portion 26 normally holds those bevel surfaces in contact with each other, whereas, when it is desired to 45 insert the traveler 13 or to detach it from the ring, dog 25 is pressed downwardly to the position shown in Figure 7.

Figures 9, 10, 11 and 12 show still another modified form in which a twisting ring 35 having 50 a traveler 36 mounted thereon is provided with the same feature. This ring 35 has a collar 37 integral with the exterior thereof which is adapted to fit down against the ring rail when the ring has been installed. The ring also has 55 an upper rim 38 and a lower rim 39, which rims are adapted to be encircled by the inturned ends of traveler 36. In order to make this ring so that the traveler 36 will be insertable thereon or removable therefrom without bending the 60 same, the upper portion of the ring has a notch 40 cut therein said notch being adapted to accommodate a dog 42 pivoted as at 43 in rim 38. The dog is normally pressed into said notch by means of compression spring 44 which is mounted 65 in recess 44a cut in rim 38. When the dog is inserted within the slot 40 the bevelled ends 45 and 46 of the dog are adapted to normally contact the bevelled portions 47 and 48 of the slot due to the normal spring pressure exerted by 70 spring 44.

Figures 13, 14 and 15 show still another modified form of the invention in which ring 35 has

a notch 50 cut in its rim 38, said notch having bevelled surfaces 51 and 52 against which bevelled surfaces 53 and 54 respectively of dog 55 are adapted to fit. The dog 55 has a spring portion 56 integral therewith which spring portion 5 is secured to the interior of the rim as at 57. This spring normally holds the dog in bold line position in Figure 13 but when a traveler is inserted or removed the dog is pressed to dotted line position to allow the open segment of the 10 traveler to pass over the remaining portion of the ring.

It is therefore seen that I have provided a ring with means embodied therein for allowing the insertion of the traveler without springing, bending or distorting the same.

In the drawings and specification there has been set forth a preferred embodiment of the invention, and although specific terms are employed, they are used in a generic and descriptive sense only, and not for purposes of limitation, the scope of the invention being set forth in the appended claims.

I claim:

1. A spinning ring having a flanged portion 25 over which a traveler is adapted to be disposed in operative position, said flange having a cut-away portion in one edge thereof decreasing its breadth and through which one end of the traveler may pass when the traveler is being inserted 30 over the flange or being withdrawn from the flange, and means normally closing the cut-away portion to prevent the escape of an inserted traveler from the ring.

2. In a spinning, twisting ring and the like 35 having a flanged portion and a web portion, said flanged portion being adapted to serve as a guide for a traveler, said flanged portion having a narrow portion whose width is not as great as the width of the remainder of the flanged portion and 40 through which narrow portion the ends of a traveler may pass in inserting or withdrawing the traveler, and means closing said narrow portion to prevent undesired escapement of an inserted traveler from the ring.

3. In spinning and twisting rings having a flanged portion for the reception and guidance of a traveler, said flanged portion having a gap therein through which the ends of a traveler may pass in inserting or withdrawing said traveler, and means for closing said gap to prevent escapement of a traveler from the ring.

4. In a textile ring having a flanged portion provided with a gap for inserting a traveler onto the flanged portion without distortion of the 55 traveler, and means for closing said gap to prevent escapement of the traveler from the ring.

5. In a ring for fiber preparation machinery having a flanged portion adapted to receive and guide a traveler, said flanged portion in one side 60 thereof having a gap and a closure member therefor and through which gap a traveler may be inserted onto or removed from the ring when said closure member is removed from the gap.

6. In a ring for fiber preparation machinery 65 having a flanged portion for reception of a traveler and provided with a gap having a removable closure member for passage of the ends of the traveler when the same is inserted onto or removed from the ring.

ROBERT Y. MCLEOD.
